UNITED STATES PATENT OFFICE.

CLARENCE W. UTZMAN, OF CHICAGO, ILLINOIS, ASSIGNOR TO THE UNITED STATES GYPSUM COMPANY, OF CHICAGO, ILLINOIS, A CORPORATION OF NEW JERSEY.

PLASTER FLOOR CONSTRUCTION.

1,174,206.

Specification of Letters Patent.

Patented Mar. 7, 1916.

Application filed August 30, 1912. Serial No. 717,838.

To all whom it may concern:

Be it known that I, CLARENCE W. UTZMAN, a citizen of the United States, residing at Chicago, in the county of Cook and State 5 of Illinois, have invented certain new and useful Improvements in Plaster Floor Constructions, of which the following is a specification.

My invention relates in general to floor 10 structures, and more particularly to floor structures such as are employed in fire-proof buildings and which are designed to meet the requirements of the Underwriters' Association.

15 One of the principal objects of the invention is to provide a floor structure which will be materially lighter in weight than the floor structures which are at present employed in fire-proof buildings, permitting thereby 20 the use of substantially lighter and consequently less expensive structural members to be used in the framework of the building.

A further object of the invention is to 25 provide a light, fire-proof floor structure which will require in its construction a minimum amount of false-work which must subsequently be removed and ultimately discarded.

30 A still further object of the invention is to provide means for reinforcing the floor structure which will be supported and sustained in position beyond the reach of excessive heat created by a fire coming in contact therewith in any part of the building.

35 Another object of the invention is to provide a floor structure wherein if the material upon the ceiling-side of the room be burned or consumed by fire, depriving it of its load-supporting strength, this material will be 40 permitted to drop into the room below, reducing thereby the load upon the upper portion of the floor structure and permitting it to offer a maximum amount of resistance to the passage of heat while retaining a minimum amount of weight to support in its 45 reduced strength.

An additional object of the invention is to so construct the parts of the floor structure that they may be transported and stored 50 until ready for use in knock-down condition if so desired and capable of being quickly and easily assembled and placed in position.

Further objects and advantages of the invention will be apparent as it is better un-

derstood from the following description which, taken in connection with the accompanying drawings, illustrates preferred embodiments thereof.

On the drawings:—Figure 1 is a partial vertical sectional view of a floor structure constructed in pursuance with my invention; Fig. 2 is a similar view showing the arrangement of the falsework and reinforcing members; Fig. 3 is a top plan view of the structure shown in Figs. 1 and 2 partially completed, showing the arrangement of the transverse reinforcing elements and the cavity-forming members in position therebetween; Fig. 4 is a partial perspective view disclosing a preferred means of securing the walls forming the cavity-forming members together at their base; Fig. 5 is a similar view showing the means fastening the said walls together at their tops; Fig. 6 is a partial perspective view of the top wall of the cavity-forming members; Fig. 7 is a top plan view of the preferred fastening means disclosed in Fig. 4; Fig. 8 is a similar view of the fastening means disclosed in Fig. 5; Fig. 9 is a sectional view of a slightly modified form of the structure shown in Figs. 1 to 3 inclusive; Fig. 10 is a view similar to Fig. 9 showing another slight modification of the structure illustrated in Figs. 1 to 3, and Fig. 11 is a vertical sectional view showing the adaptation of the floor structure to floors provided to sustain somewhat heavier loads than the floors constructed in accordance with Figs. 1 to 3.

For the purpose of illustrating my invention an embodiment of the same is shown on the drawings in various stages of completion and in various modifications connected to and supported by the structural I-beams 95 such as are usually employed in fire-proof buildings. The finished structure is composed primarily of a central layer 16 of stucco or other cementitious material which is adapted to bond with a layer of plaster-board 17 disposed therebeneath and which preferably retains in its set condition a relatively large percentage of water. In this layer of stucco or cementitious material are provided a plurality of cavities 18 formed 100 by boxes 19 of plaster-board or other material which will bond with the stucco and which will not shrink or expand as the floor 105 dries out. Between these cavity-forming members or boxes a plurality of transverse 110

2
rods 21 are provided, and upon them and beneath the cavity-forming elements is disposed and embedded in the layer of stucco 16 a sheet of expanded metal or wire fabric 20 upon which the bottom edges of the boxes preferably rest. The rods 21 are preferably twisted or roughened to enable them to be more firmly retained in the stucco, and to more efficiently reinforce the same. These 5 rods are, in the embodiment of the invention shown in Figs. 1 to 3, arranged in pairs and secured at their ends to the opposite I-beams 15. For this purpose the ends 22 of the rods 21 are looped over the upper outer 10 horizontal flanges of the I-beams, and these rods are preferably depressed throughout their central portions, as at 23, to lie adjacent the lower or ceiling side of the floor structure, the depressed portions, however, 15 being spaced a sufficient distance from the ceiling side of the structure to provide the required depth of fire-proofing material or stucco between the said rods and the ceiling of the room beneath. As shown in Figs. 1 20 to 3, a plurality of pairs of rods extend between each parallel pair of I-beams, dividing the space inclosed by the I-beams into approximately equal rectangular spaces. The rods disposed in one direction are all preferably deflected at their central portions an amount sufficiently greater than the deflection of the rods disposed at right angles thereto to permit the second set of rods to 25 rest upon the first set. A shorter rod 24 is employed in connection with each pair of the longer rods at each side, and preferably disposed therebetween, one end of the shorter rod resting upon the lower inner horizontal flange of the I-beam and the 30 other end resting upon the nearest pair of longer rods disposed at right angles thereto, as is perhaps best seen in Fig. 2. The fabric or sheet 20 is preferably disposed over the rods 21 and 24 beneath the cavity-forming 35 members or boxes 19, and is preferably cut into strips to fit between the rods running in one direction in order that it may be easily positioned.

50 The cavity-forming members or boxes are preferably constructed of plaster-board, as this material does not shrink or expand under varying conditions, and is unaffected by the degree of moisture contained therein or in the surrounding cementitious material. 55 The boxes 19 are preferably open at their bottom, and formed of an appropriate number of side walls 25 and a top member 26. These side walls may be joined together in any efficient and desired manner, but to provide 60 boxes for this purpose which may be economically transported and stored until required in the construction of the floor I have shown on the drawings a knock-down box which may be readily set up, and which is preferably constructed as immediately

hereinafter described. Bottom clamps 27 and top clamps 28 are used to securely fasten the corners of the side walls together. Each of the clamps 27, preferably formed of sheet metal, is provided with an upstanding flange 70 29 at each side of the rectangular corner 31, and similar although shorter flanges 32 adapted to be disposed within the cavity-forming member to engage the side walls internally of the box. The flanges 32 are 75 preferably formed by stamping a portion of the clamp 27 upwardly, as shown in Fig. 4, the rear portion of the clamp being left intact and having its edges bent to permit it to form a stiffening brace 33. The top clamp 28 is cut away at its front, and the outer side edges 34 bent down at right angles to each other to form flanges to embrace the outer faces of the top of the side walls adjacent the corner. The intermediate portion 80 of this clamp is pressed downwardly as shown in Fig. 5 to form walls 35 engaging the inner surface of the side walls, the depressed portion 36 forming a support for the corner 37 of the top member 26, permitting the upper surface of this top member to lie substantially in the same plane with the upper edges of the side walls. One or more plaster-boards may be employed in forming each side wall and top member, one 95 of the boards being shown in Figs. 4, 5 and 6, and four shown in Fig. 1.

In Fig. 9 a slight modification in the arrangement of the reinforcing rods is disclosed. In this construction one of each pair 100 of parallel rods is continued substantially horizontally from the I-beam 38 until it reaches the first pair of rods 39 and 41 disposed at right angles thereto. This rod 42 is at that point bent downwardly to the 105 second pair of parallel rods 43 where it becomes parallel with its companion rod 44. Between the rods 39 and 41 an angle plate 45 is employed to separate the rods 39 and 41 and the rods 42 and 44, this plate resting 110 merely upon the rods 39 and 44 and spacing apart therefrom the rods 41 and 42.

In Fig. 10 the rods 46 which extend completely across the structure between the I-beams 47 are disposed throughout their 115 length in a horizontal plane, and are continuous throughout the construction, suitable apertures 48 being provided through the web of the I-beam for this purpose. The shorter reinforcing rods, which are in this 120 instance secured to the outer upper horizontal flange 49 of the I-beam, as at 51, are inclined within the floor structure and looped about the pair of transverse rods 46 as seen at 52. In Fig. 10 is also shown the means 125 of providing a floor structure of any of the embodiments with an I-beam having a greater depth than the necessary depth of the floor. As the underwriters require that a certain amount of cementitious or other 130

material of high fire-resisting qualities be interposed between the iron-work and the interior of the building, the lower flange 53 of the I-beam 47 is provided with a pair of blocks 54 which are recessed at 55 to receive and fit upon the lower flanges 53. These blocks are of such dimension that all points of the I-beam are at the required distance from the interior of the room, and are protected by the required amount of fire-proofing material. In this figure also is shown a vertical reinforcing sheet 56 of expanded metal or wire fabric which when deemed desirable may be employed in connection with any and all embodiments and adaptation of the floor structure shown and described herein.

In Fig. 11, which is probably the embodiment of the invention best adapted to support extremely heavy loads, a plurality of channel irons 57 are connected together by fish plates or angle irons or other suitable structural metal 58, the channel irons being so arranged that the space between the angle irons is divided in much the same manner as the space between the I-beam 15 is divided by the pairs of reinforcing rods 21. Secured at the junctions of these channel irons adjacent the corner formed by each pair of I-beams is provided an angular upright plate 59 supporting a pair of reinforcing rods or members 61 and 62. These rods or members may either be hooked around the upper outer horizontal flange of the I-beam in a manner similar to that hereinbefore described, or each rod or member 61 and 62 may be disposed over the I-beam as shown at 63, the ends thereof serving to reinforce the floor structure upon opposite sides of the I-beam and in adjacent spaces. The end of the rod within the floor construction is bent downwardly beyond the plate 59 to provide the inclined portion 64 secured to the fish or angle-plates 58 at the intersection of the channel irons next beyond the intersection of the channel irons at which the angle plate 59 is located. The companion reinforcing member 66 is shorter in length, and is bent downwardly immediately upon leaving the I-beam, and is secured to the angle or fish-plate 58 disposed at the intersection of the channel irons at which the angle plate 59 is secured.

In constructing any of the floor structures hereinbefore described false work composed of a plurality of supporting rafters 68 and 69 are secured in position to support the plaster-board 17, which forms the platform for the reception of the stucco or cementitious material. When the plaster-board is in position the main and auxiliary reinforcing and supporting rods are positioned, and the strips of the reinforcing sheet 20 of wire or expanded metal are laid over them in the manner described. A quantity of stucco or

cementitious material in a plastic or semi-liquid state is now poured upon and through the sheet of expanded metal until the space between it and the plaster-board is filled and the reinforcing sheet completely covered. Upon this layer of stucco or cementitious material and in the spaces formed between the rods are now positioned the cavity-forming elements or boxes which settle into the cementitious material until their open bottoms rest upon the fabric. More stucco or cementitious material, preferably identical in composition with that first placed upon the plaster-boards, is now added until the tops of the cavity-forming members and the rods and angle-irons are submerged, and a smooth even surface of cementitious material of desired minimum depth is provided. In the upper surface of this cementitious material are secured a plurality of wooden or composite furring strips 71 upon which the rough flooring 72 is subsequently nailed and the finished flooring 73 positioned. Where a concrete flooring is desired, however, the concrete 74 may be deposited directly upon the stucco, as shown in Figs. 10 and 11. The stucco or cementitious material bonds permanently and efficiently with the upper surface of the plaster-board as it becomes set, at which time the beams 68 and 69 are removed. The finishing plaster 75 may then be applied, and the paper or finish 76 subsequently applied thereto, the plaster-board bonding as readily with the finishing plaster 75 as with the cementitious material immediately above it.

It will be manifest that I have provided a floor construction of minimum weight retaining a relatively large percentage of water, capable of resisting the desired strains and supporting desired weights, and which is of high fire-resisting qualities, and which can be readily made to comply in every way with the building and underwriters' regulations in all localities by various changes of dimension.

It will be apparent that various changes may be made in the form, material and arrangement of the various elements of the structure, and numerous modifications made in the method of constructing the same without departing from the spirit or scope of my invention, or sacrificing any of its advantages.

I claim:—

1. A floor and ceiling construction comprising supporting beams, reinforcing members supported by said beams, a layer of plaster disposed between said beams and surrounding said reinforcing members, and means adhering to the lower surface of said plaster and forming a support therefor during the process of erection.

2. A floor and ceiling construction comprising supporting beams, reinforcing mem-

120

125

130

bers supported by said beams, a layer of plaster disposed between said beams and surrounding said reinforcing members, cavity-forming members disposed within the 5 layer of plaster between the reinforcing means, and means adhering to the lower surface of said plaster and forming a support therefor during the process of erection.

3. A floor and ceiling construction comprising supporting beams, reinforcing mem-

bers supported by said beams, a layer of plaster disposed between said beams and surrounding said reinforcing members, and a layer of plaster board adhering to the lower surface of said plaster and forming a support therefore during the process of erection. 15

CLARENCE W. UTZMAN.
